UNITED STATES PATENT OFFICE.

CHARLES J. DUDLEY, OF NORTH TONAWANDA, NEW YORK, ASSIGNOR TO AMERICAN DISTRICT STEAM COMPANY, OF NORTH TONAWANDA, NEW YORK, A CORPORATION OF NEW YORK.

VALVE.

1,217,579.

Specification of Letters Patent. Patented Feb. 27, 1917.

Application filed April 25, 1914. Serial No. 834,512.

To all whom it may concern:

Be it known that I, CHARLES J. DUDLEY, a citizen of the United States, residing at North Tonawanda, in the county of Niagara and State of New York, have invented certain new and useful Improvements in Valves, of which the following is a specification, reference being had therein to the accompanying drawing.

10 This invention relates to valve structures and appertains to that class thereof which are utilized in connection with steam radiators.

15 The primary object of the invention is to provide a valve of the kind specified wherein the co-acting parts are so aggregated and related that the quantity of the passing fluid, etc., may be accurately predetermined.

20 It is a further object of my invention to provide an efficient form of valve that is simple in design and construction and in which the essential instrumentalities provided are so aggregated that certain of these 25 are replaceable for purposes which will hereinafter be set forth.

The invention in general seeks to provide a valve structure which, as already specified, is particularly adapted for use in connection with steam radiators and which structure from an operative standpoint, will in 30 practical use possess a high degree of efficiency and durability.

Other objects and advantages will in part be obvious from the annexed drawings and 35 will also be in part pointed out in the following description.

The invention resides broadly in the features of construction, combinations of elements, and arrangements of parts, and in 40 various aggregations thereof, all as will be exemplified in the construction hereinafter set forth, and the scope of application of which will be indicated in the claims hereto appended.

45 In order that this invention may be clearly comprehended by those skilled in the art, drawings illustrative of one of the many possible embodiments of the same are hereto appended as a part of this specification; it 50 being manifest that other possible embodiments employing the underlying principles

of my invention fall within the spirit thereof and within the objects contemplated thereby.

55

In these drawings:

Figure 1 is a view in vertical section of a valve-structure embodying my invention, the parts being in such position that the valve is closed;

Fig. 2 is a fragmentary view, in vertical section, showing the valve open;

Fig. 3 is a view in horizontal section, on the line 3—3, Fig. 2, the split-ring being shown, in this instance, as having been turned somewhat to bring its ends into view, similarly as in Fig. 2;

Fig. 4 is a fragmentary view in elevation looking into one of the openings in the valve-body;

Fig. 5 is a collective view of the insert member, in elevation and in vertical and horizontal section, respectively; and

Fig. 6 is a similar view of the split member-retaining ring.

Referring to the drawings, the reference-character 1 designates a casing which obviously may be of any preferred form and construction, provided that it includes an inlet port 2 and an outlet port 3. In this instance, the outlet port is formed in the 80 tubular portion 4 arranged at an angle to the casing, and which is in communication, through said outlet port 3 and an opening 20, with a chamber 5, on the interior of the casing.

85

Upon the outside of said casing, at its upper portion, there is provided a circumferential enlargement or flange 6 which may be graduated or otherwise marked, for a purpose presently to be explained. This 90 casing, etc., constitutes one component of the valve structure.

The casing is, preferably and as shown, provided with an upwardly-extending portion 7, which is threaded to receive an internally and externally threaded sleeve 8 that at its lower end extends into the chamber 5. The sleeve is provided at its lower end with threads 9 and, at its upper end, with threads 10. Into the upper threaded portion is screwed a bearing member 11. Extending through this bearing member is

95

100

a valve stem 12 which is provided with screw threads 13 adapted to engage the inner threads 9 in the sleeve 8. The stem, at its lower end, carries a head or enlargement 14 provided with an annular recess 15. The head and the stem on which it is formed constitute one of the active means for controlling the passage of steam or the like through the outlet and, according to its particular position therein, operates to close said port entirely, or to open it to varying degrees.

The stem is rotated manually, and this operation is facilitated by the hand-piece 16, which is preferably detachably secured to the upper end of the stem, as shown.

Also secured to the stem, in any preferred manner, is a pendent collar 17, the lower portion of which occupies an annular recess 18 formed between the upper end of the sleeve 8 and the casing. Mounted upon this collar is an indicator extension 19 adapted to overlie the graduated flange 6, as shown in Fig. 1, and to coöperate with graduations thereon (not shown) to indicate to the operator the relative position of the fluid-controlling instrumentalities.

As shown in Figs. 1, 2 and 3, the portion 4 of the casing is provided with an opening 20 of a vertical dimension less than the vertical dimension of the stem-carried head 14. Seated in this opening is a reducer element or flow-determining member 21 comprising a disk portion 22 and two rearwardly-extending portions 23, between which there is formed, in the disk, an opening 24 which, in this instance, is shown as rectangular, though it may be of any other desired or required form. The disk portion of the element occupies an operative position in a recess 25 formed in the vertical wall of the portion 4. The rearwardly-extending portions 23 project through the opening 20 and beyond the exterior plane of the head 14. To this end, the portions 23 are cut on an arc so that the curved edges thereof embrace the periphery of the head 14. Any suitable means may be provided for retaining the reducer element 21 in operative position. In this instance, I have shown, as an example of such means, a resilient member 26, in the form of a split-ring. The ring is adapted to be sprung into a groove 27 formed in the portion 4 of the casing. When the head 14 is in its lowermost position, it abuts against a flange 28 formed in the casing and, when in this position, said head entirely closes the opening 24, as shown in Fig. 1. When the stem is manipulated to elevate the head away from the flange 28, it will, in progressive degrees, permit a flow of fluid between the portions 23 and through the opening 24 of the reducer element and out through the outlet port 3. The preferred

uppermost position of the head is illustrated 65 in Fig. 2, and, when in this position, the valve is entirely open.

The opening 24 is of predetermined size and is accurately milled, to an accuracy of a thousandth of an inch, to produce a width 70 to permit a predetermined quantity of steam to flow therethrough, according to the size of the radiator to which the valve is to be attached. It is to be understood that there may be a series of these reducer elements 75 provided with differently-sized openings to accord to predetermined calculations, whereby a predetermined quantity of steam may pass therethrough. In other words, their size bears a definite ratio to the normal pressure of the steam and the volume and size of the radiator to be supplied; that is to say, if the size be, say, 60 sq. ft., the opening 24 will be cut so that no more steam, under a five-ounce pressure, (say) can pass through the 80 valve and into the radiator than will fill, for instance, a sixty-foot radiator up to 85% of its capacity or volume. Thus, it will be seen, no steam can be wasted, since less than the maximum capacity of the radiator is 90 provided and, in this way, over-heating of the radiator and waste of steam are avoided.

From the foregoing it will be perceived that I have succeeded in devising a valve-structure which is well adapted to achieve 95 the several objects and ends in view. The structure is compact in form, is characterized by simplicity, and the parts are so formed and constructed as to permit of its ready application.

As many changes may be made in the construction herein disclosed and many widely different embodiments of the invention can be made without departing from the spirit thereof, it is intended that all matter contained in the foregoing description and shown in the accompanying drawings shall be interpreted as illustrative and not in any limiting sense.

It is also to be understood that the language used in the following claims is intended to cover all of the generic and specific features of the invention which, as a matter of language, might be said to fall therebetween.

What I claim is:

1. A valve structure comprising in combination, a casing provided with an inlet and outlet port, and having a chamber with which said ports communicate; said casing also having a head portion including a collar provided with an internally threaded opening; a partition extending across the inlet port and provided with an opening arranged to form a valve seat; a sleeve threaded into the opening in the head of the casing and having its inner portion disposed within the chamber, said sleeve being also thread-

- ed internally at its inner and outer extremities; a valve stem having at one end a head adapted to rest on the valve seat and at its other end an operating instrumentality, said 5 stem being threaded intermediate its ends into the threaded interior of the sleeve; a bearing surrounding the valve stem and threaded into the outer end of the sleeve; a partition extending across the outlet port, 10 said partition being provided with an opening, and with a recess formed around said opening; and a closure restricting member comprising a disk portion disposed in the recess, and having portions projecting 15 through said opening and bearing against the valve-head.
2. A valve structure comprising in combination, a casing provided with an inlet and outlet port, and having a chamber with 20 which said ports communicate; said casing also having a head portion including a collar provided with an internally threaded opening; a partition extending across the inlet port and provided with an opening 25 arranged to form a valve seat; a sleeve threaded into the opening in the head of the casing and having its inner portion disposed within the chamber, said sleeve being also threaded internally at its inner and 30 outer extremities; a valve stem having at one end a head adapted to rest on the valve seat and at its other end an operating instrumentality, said stem being threaded intermediate its end into the threaded in- 35 terior of the sleeve; a bearing surrounding the valve stem and threaded into the outer end of the sleeve; a partition extending across the outlet port, said partition being provided with an opening, with a recess 40 formed around said opening, and with a groove disposed back of said recess; an outlet restricting member comprising a disk portion disposed in the recess and projecting members having curved edges passing 45 through the opening in the partition and bearing against the valve head; and a retaining instrumentality seated in the groove and bearing against the disk-portion of the outlet restricting member.
- 50 3. A valve structure including in combination a casing having a tubular portion comprising an outlet port and communicating with the interior of the casing through an opening, said casing having 55 also an inlet port and an upper surface, a stem rotatably mounted in said casing and 60 carrying a pointer associated with said upper surface and bearing a definite relation thereto, a head carried by said stem and having a to-and-fro movement in the casing, and an insert-member provided with 65 an opening of a predetermined size to act as a reducer, said member being disposed within said tubular portion of the casing, and occupying a position in said opening so as to be slidably engaged by a peripheral 70 portion of the head in its to-and-fro movement.
4. A valve structure including in combination a casing having a tubular portion comprising an outlet port and communicating with the interior of the casing through an opening, said casing having also an inlet port and an upper surface, a stem rotatably mounted in said casing and 75 carrying a pointer associated with said upper surface and bearing a definite relation thereto, a head carried by said stem and having a to-and-fro movement in the casing, an insert-member provided with an opening of a predetermined size to act as a 80 reducer, said member being disposed within said tubular portion of the casing, and occupying a position in said opening so as to be slidably engaged by a peripheral portion of the head in its to-and-fro movement, 85 and an annular element disposed in engagement with said member to retain it in position and in operative engagement with said head.
5. As an article of manufacture for use 90 in restricting ports of valve structures, a disk member adapted to seat in a recess formed around an opening in a valve casing, said disk being provided with an opening; and members secured at their inner 100 ends to the face of the disk, the outer ends of said members being arcuately curved to correspond with the periphery of a valve head, said members being adapted to pass through the opening in the casing and bear, 105 at their arcuately curved portions against a periphery of the valve head when the disk is seated in the recess.

In testimony whereof I affix my signature
in presence of two witnesses.

CHARLES J. DUDLEY.
